UNITED STATES PATENT OFFICE.

PAUL A. VANCZO, OF RAHWAY, NEW JERSEY.

HAND SAWING-MACHINE.

1,173,902.

Specification of Letters Patent. Patented Feb. 29, 1916.

Application filed April 23, 1915. Serial No. 23,476.

To all whom it may concern:

Be it known that I, PAUL A. VANCZO, a citizen of the United States, residing at Rahway, in the county of Union, State of New Jersey, have invented certain new and useful Improvements in Hand Sawing-Machines; and I do hereby declare the following to be a full, clear, and exact description of the invention, such as will enable others skilled in the art to which it appertains to make and use the same.

This invention relates to a hand sawing machine.

An object of the invention resides in the provision of a device which may be operated by the ordinary carpenter's brace.

A further object of the invention resides in so constructing the device that it may be used to saw a board from a floor without necessitating the boring of holes in the floor before the sawing operation.

A further object of the invention resides in so constructing the device that when it is being operated the saw will be fed through the work against the action of a spring which will return the saw to its initial position upon the completion of the sawing operation, and the removal of pressure from the brace.

With these and other objects in view, such as will appear as my description progresses, my invention comprises the combination and arrangement of parts as set forth in and falling within the scope of the appended claim.

In the accompanying drawings: Figure 1 is a front elevation of my device. Fig. 2 is a side elevation thereof. Fig. 3 is a vertical sectional view taken longitudinally of the saw shaft. Fig. 4 is a top plan view. Fig. 5 is a horizontal sectional view on line 5—5 of Fig. 1. Fig. 6 is an enlarged detail showing the manner of mounting the saw upon the shaft.

Referring to the drawings by reference characters wherein like parts are indicated by like characters throughout the several views: In the embodiment of my invention shown in the drawings, I have provided a frame which comprises a head 1, and a pair of standards 2 and 3 which are mounted upon a base 4. This base is provided with a plurality of spurs 5 which may be forced into the work to secure the frame in position. Each of the standards 2 and 3 is provided with a vertically extending slot 6, while the head 1 is provided with a pair of

parallel holes 7 and 8. This frame is made in two sections, for convenience of assembly, which are secured together by suitable bolts 9.

Mounted between the standards 2 and 3 and arranged to have vertical sliding movement, is a shaft support 10 which is of inverted U shaped formation, and has a pair of guides 11 formed thereon which are operable in the slots 6. Formed on the outer faces of these guides 11 are flanges 12 which bear against the outer faces of the standards 2 and 3. Rotatably mounted in the legs of the support 10 is a horizontally disposed shaft 13 which has a head 14 on one end thereof bearing against the outer face of the adjacent flange 12. A second head 15 is formed on the shaft and bears against the inner face of the adjacent leg of the support 10. These heads 14 and 15 prevent the lateral movement of the shaft 13. The end of the shaft 13 opposite to that on which the head 14 is formed is extended beyond the outer face of the adjacent flange 12 and is reduced to form a shoulder 16. Formed on this end of the shaft is a disk 17 which overhangs the shoulder 16, and provides a chamber 18. A circular saw 19 is mounted upon this end of the shaft, the hole therein being greater in diameter than the diameter of the shaft, and less than the diameter of the chamber 18. This saw bears against the face of the disk 17. In order that this saw may be clamped upon the shaft 13, I have provided a plate 20 which has a hole therein through which the shaft 13 passes, and a chamber 21 formed therein. Slidably mounted on the shaft 13 is a sleeve 22 which has a portion extending outwardly from the chamber 21, and a head 23 for limiting the outward movement of the sleeve from the chamber. A coil spring 24 encircles the shaft 13, and bears against the head 23 so as to normally push the sleeve 22 outwardly. The inner face of this plate 20 is adapted to contact with the outer face of the saw 19 while the sleeve 22 extends through the hole in the saw into the chamber 18. The saw 19 is clamped between the disk 17 and the plate 20 by a nut 25 which is adjustably mounted on the end of the shaft.

In order that the support 10 may be normally held in a position adjacent the head 1 of the frame, I have secured a coil spring 26 to the right portion thereof which ex-

tends upwardly through the hole 8 in the head, and is secured to a button 27 which bears against the upper face of the said head.

5 In order that the saw may be rotated, I have provided a beveled gear 28 which is located on the shaft 13 between the legs of the support 10. Rotatably mounted in the bight portion of the support 10 is a shaft 10 29 which has a beveled gear 30 on one end thereof which gear meshes with the gear 28. This shaft 29 extends upwardly through the hole 7 in the head 1 of the frame, and is rotatable and slidable therein. The upper end of this shaft 29 is 15 squared so that it will fit into the jaws of the ordinary carpenter's brace.

In operating the device, assuming that it is desired to cut a board from a floor, the 20 squared end of the shaft 29 is engaged by the brace, and the frame placed upon the floor so that the spurs 5 penetrate the same. The brace is then pushed downwardly until the saw 19 contacts with the floor at which 25 time the crank portion of the brace is rotated. This movement imparts a rotative movement to the saw. During this rotative movement of the saw a constant pressure is applied to the end of the brace which will 30 feed the saw through the floor against the tension of the spring 26. It will thus be seen that a board may be cut from the floor without necessitating the boring of a hole in the floor or the chiseling of a piece from 35 the floor to accommodate the end of a saw.

It will thus be seen that I have provided

a device which may be readily attached to and operated by a carpenter's brace.

While I have illustrated and described a particular embodiment of my invention it 40 has merely been for the sake of convenience, and I wish it to be understood that I am aware of the fact that numerous changes in the details of construction may be made, and I therefore do not wish to be limited 45 to the particular embodiment shown any more than is necessary by the scope of the claim.

What I claim is:—

A portable circular saw machine comprising 50 a frame, a support slidable in said frame, a shaft carried thereby and a saw thereon, a shaft at right angles to and geared to said first mentioned shaft and slidable with said support in said frame and having 55 an end projecting beyond said frame and adapted to be engaged by a bit-stock to be rotated thereby and to be pressed thereby toward one end of said frame, a spring tending to maintain the support 60 away from one end of the frame so that the saw shall not project beyond said end but permitting it to be thrust beyond said end into engagement with work engaged thereby. 65

In testimony whereof, I affix my signature, in the presence of two witnesses.

PAUL A. VANCSO.
